UNITED STATES PATENT OFFICE.

DANIEL E. PARIS, OF TROY, NEW YORK.

DRAFT-DOOR AND CHECK-DRAFT.

SPECIFICATION forming part of Letters Patent No. 353,964, dated December 7, 1886.

Application filed December 31, 1884. Renewed June 25, 1886. Serial No. 206,270. (No model.)

To all whom it may concern:

Be it known that I, DANIEL E. PARIS, a citizen of the United States, residing at Troy, Rensselaer county, New York, have invented 5 new and useful Improvements in Draft-Doors and Check-Drafts, of which the following is a specification.

It is the purpose of my invention to provide a draft-door for stoves, whereby the draft may 10 be perfectly and easily regulated by an adjustment of the simplest character, the device being applicable to stoves of all classes.

To this end my invention consists in the combination of devices, hereinafter described and 15 claimed.

Referring to the drawings, Figure 1 is a perspective view showing a portion of the front of the stove in which my invention is embodied. Fig. 2 is a horizontal section showing the 20 slide-plate and draft-door, together with a portion of the stove-wall, the actuating-slide being shown in dotted lines.

In the said drawings, the reference-numeral 1 denotes the wall of the stove, which may be 25 of any suitable style of construction. I have shown in the drawings a surface-burning stove; but it should be understood that this invention is equally applicable to any other class 30 of stoves in which heat is generated by the consumption of any kind of fuel.

At a suitable point within the wall of the stove is formed a draft-opening, 2, and upon the stove-wall in front of said opening is hinged or pivoted a draft-door, 3, by which said opening 35 may be closed to exclude the admission of air. If desired, this draft-door may be illuminated by the insertion of mica plates 4.

Upon the wall of the stove, beneath the draft-door 3, is formed or attached a slide-supporting 40 plate, 5, which, as shown in the drawings, lies substantially in a horizontal plane, its surface being at a right angle with the wall of the stove, although such an arrangement is not essential, as the surface of said plate may be inclined at 45 any suitable angle with the stove-wall.

Within the slide-plate 5 are formed parallel slots 6, which are cut diagonally relatively to said plate, forming an acute angle with the wall of the stove upon which the slide-plate 5 is 50 mounted. These slots receive guide pins or studs 7, which depend from an actuating-slide, 8, mounted and moving upon the plate 5. A

handle, 9, is formed upon slide 8, by which it may conveniently be operated, and it will readily be seen by moving it longitudinally upon the slotted support 5 it may be caused to approach and recede from the stove-wall by reason of the diagonal arrangement of the slots 6, which receive the guiding studs 7.

Upon or near the central portion of the draft-door 3 is formed or attached an arm, 10, which is bent outward and then downward from its point of attachment, and enters a slot, 11, formed in the horizontally-movable slide 8, the inner and outer walls of said slot acting as a cam on the arm 10 by reason of the slide moving both horizontally and laterally to and from the front plate of the stove. I therefore term the slot a "cam." The arrangement of these parts is such that when the actuating slide 8 is pushed to the ends of the slots 6, which are most remote from the wall of the stove, the draft-door will be thrown into close engagement with the opening 2, closing it against the admission of air, whereas by moving the actuating-slide in the opposite direction the door is thrown open. By varying the longitudinal adjustment of said slide the draft-opening may be increased or diminished to any desired degree.

Above the draft-door 3 is formed an opening, 12, for the check-draft. This aperture may be wholly or partially closed by a sliding door, 13, which may, if desired, be arranged in the strip 14 and be provided with mica panes, as is the said strip for illuminating purposes.

The check-draft is so placed that the air admitted through it will pass above the burning fuel, thereby lessening the force of the current entering at the draft-opening and passing upward through the grate. By a very simple 90 adjustment of the one relatively to the other the fire may be controlled with perfect ease, and may be brought to and retained at the exact point required.

The draft-door 4 is illuminated by mica, 95 whereby increased radiation and greater light are obtained, and the beauty of the stove is enhanced.

What I claim is—

1. The combination of a stove having a draft-opening, a hinged door, a slide-supporting plate, and a horizontally-movable slide supported and guided by the plate, and having a cam connected with the door, substantially as described.

2. The combination, with a stove having a draft-opening, of a hinged door, a stationary diagonally-grooved slide-supporting plate rigidly connected with the stove, and a horizontally-movable slide having projections engaging the grooved part of the plate and loosely connected with the door, substantially as described.
3. The combination, with a stove having a draft-opening, of a hinged door, a stationary slide-supporting plate having diagonal guides, and a horizontally-movable slide engaging and guided by the guides of the plate and loosely connected with the door, substantially as described.
4. The combination of a stove having a draft-opening, a diagonally-slotted slide-supporting plate, a hinged door having an attached projecting arm, and a horizontally-movable slide having projections engaging the slotted part of the plate and loosely engaging the arm of the door for locking the same at any angle of inclination, substantially as described.
5. The combination, with a stove provided with a draft opening, of a hinged draft-door having an attached projecting arm, a diagonally-slotted slide-supporting plate, and a slide having a slot engaging said arm, and provided with studs or pins engaging the slots in the supporting plate, substantially as described.

In testimony whereof I affix my signature in presence of two witnesses.

DANL. E. PARIS.
